BY Fisher & Moser ATTYS

UNITED STATES PATENT OFFICE.

WILLIAM C. TREGONING, OF CLEVELAND, OHIO.

SOCKET FOR INCANDESCENT LAMPS.

No. 918,102.

Specification of Letters Patent. Patented April 13, 1909.

Application filed June 26, 1908. Serial No. 440,443.

To all whom it may concern:

Be it known that I, WILLIAM C. TREGONING, a citizen of the United States, residing at Cleveland, in the county of Cuyahoga and State of Ohio, have invented certain new and useful Improvements in Sockets for Incandescent Lamps, and do declare that the following is a full, clear, and exact description of the invention, which will enable others skilled in the art to which it appertains to make and use the same.

My invention relates to sockets for incandescent lamps, and the invention consists in a socket having definitely related and uniform contact surfaces which do not change or diminish in area from the making to the breaking of the circuit and which are constructed and adapted to operate, substantially as shown and described and particularly pointed out in the claims.

In the accompanying drawings, Figure 1 is a sectional elevation of the socket with the contact members open. Fig. 2 is a sectional elevation of the socket a quarter turn to the right as compared with Fig. 1, and Fig. 3 is a sectional elevation corresponding to Fig. 2 with the shell and one of the terminal connecting parts removed and with the contact members closed. Fig. 4 is a perspective view of the two contact members. Fig. 5 is a perspective view of the rotatable ratchet member. Fig. 6 is a cross section corresponding to line 6—6, Fig. 2 looking down, and Fig. 7 is a cross section turned through about a sixth of a revolution on a line corresponding to 7—7, Fig. 3, looking down. Fig. 8 is a perspective view of one of the terminal connections, and Fig. 9 is an enlarged sectional elevation of the socket as a whole with the closing shell removed and the circuit open corresponding to Figs. 1 and 2. Fig. 10 is a perspective view of a post or spindle on which the operating lever is mounted, and Fig. 11 is a perspective view of the spring upon said post. Fig. 12 is a perspective view of the operating lever, and Fig. 13 is a side view of the socket.

In the drawings as thus shown S represents the socket member or portion proper, the same being of conducting material and adapted to have the lamp screwed or turned to engaging position therein much as usual, and c is a contact extension adapted to be electrically engaged by the lamp and forming a part of the terminal connecting member C. The current is carried in the outer portion of

the circuit through this member, which has a binding screw 2 for the wire at the side of said member.

A and B are the upper and lower insulation disks or parts respectively, which carry the current conducting parts as usual and are rigidly united but held apart relatively by the terminal connecting members C and D. The usual shell E incloses said parts and is insulated about its inside from the socket S and other parts. Said disks A and B may be made of porcelain, fiber or other acceptable material.

Now, having the said several parts constructed and arranged as thus shown and described, or in equivalent form, sundry novel and original features are employed therewith and which clearly differentiate the invention from all the prior art known to me, and the said parts comprise the two contact members 4 and 5, the insulating rotatable ratchet member 6, controlling arm 7, the post or shaft 8, and the spring 9 mounted on said post. The said several parts also are of novel construction individually. Thus, the said contact members 4 and 5, through which the circuit is made and broken alternately, are peculiar and original in this, that they are stationary as to their position in the socket and permanently fixed on the opposed insulating disks A and B at corresponding ends by the respective screws 10 and 12. The said parts consist of flat thin pieces of spring metal curved edgewise between their ends to a segment of a circle conforming to the curvature of the socket and are suitably fashioned at their respective right angled fastening ends 13 and 14 respectively to be secured by the screws 10 and 12 and to bring said members otherwise into substantially parallel planes between their contact portions. These portions comprise the outer half of said members between points x and y, and said members are further characterized by a mutual and corresponding bend of the said outer half thereof at x in the direction of rotatable ratchet member 6 and so as to engage with said member and thereby make and break circuit as well as to hold said member with each rotation. To these ends the said parts 4 and 5 serve also as pawls which hold whatever rotation the ratchet is given in a forward direction by lever 7 and prevent reverse rotation thereof,

thereby assuring successive making and breaking of the circuit and limiting the ac-

tion of the device to either one or the other in any single pull on the chain 16 by which a person turns the current on or off. Normally the said two contact members 4 and 5 are apart or out of contact, as seen in Figs. 1, 2 and 4, and in that position bear against the shoulder *a* of the ratchet member at their extremities. Then when contact or closing of the circuit is to occur the said ratchet member is given a quarter turn ahead by pulling on chain 16 and the two contact members are pressed together into touch their full contact length as they ride up over transverse rib or tooth *b* and drop behind the same and into stop engagement therewith, as in Fig. 3. One or both said contact members may engage said tooth, according to its depth, but one will suffice as it serves the double purpose of checking the reverse rotation of ratchet 6 and throws the two contact members into electrical closure on their otherwise flat surfaces between points *x* and *y*. In this operation the inner surface *d* of the ratchet next to the tooth or rib *b* engaged at the time rests the said contact members and presses them together. Then as they ride off this surface or face they spring apart of their own accord and lock against edge *a* and the circuit is broken. It has been observed that by this construction the usual wiping or traveling contact is wholly avoided, and that when contact is made it occurs uniformly and at the same instant the entire length and width between the points *x* and *y*, and when contact is broken it occurs in like manner over all said surface simultaneously. Hence there is no running or moving contact, as is common, and which inevitably brings the parts to a sparking relation at least, if not to burning out, where they gradually travel to the termination of contact and snap apart. In the present construction there is no such travel of any part in respect to the other and no reduction of the contact surface, but the free ends of the contact members separate alike and at the same time from *x* to *y* by simply springing apart and breaking the circuit uniformly over the whole of said surface at the same time. Again, the operating lever 7 has a hub *h* loosely mounted on post or shaft 8 so as to rotate alone thereon within limits, and said arm has a pawl or finger *g* adapted to engage successively on the said teeth *b* and shoulders *a* on ratchet member 6 and thereby rotate said member within the limits provided. These limits are defined by the space between studs *m* and *n* on the inner edge of insulating disk *B*, and said lever rests normally back against stud *m* and is moved to contact with stud *n* as its definite stop when the lever is operated to make or break circuit. It occurs, therefore, that pawl *g* always engages one or the other of the teeth *b* or shoulders *a* when at rest, so as to

be in readiness to move the ratchet member forward when an operation is to take place, and spring 9 about the said post is engaged at one end on stud 20 on said lever and at the other end in one of the several notches *e* in the lateral flange on the inner end of said post or shaft 8. By changing the spring into one or the other of said notches the tension thereof can be changed accordingly. The action of the spring is to throw the operating lever back after a forward rotation by hand and thereby bring the lever into engagement with the next succeeding tooth *b* or shoulders *a* after it has carried the ratchet member forward a quarter turn and made or broken circuit as the case may be.

The line wires are adapted to be connected at or by the respective binding screws 2 and 3, and the circuit is completed in one case through terminal member *C* and in the other through terminal member *D*, with the contact members 4 and 5 in the latter portion of the circuit.

The ratchet member 6 is of a two wing or two leaf pattern, with a hub *h* having a bore free to turn on fixed shaft 8 and with said wings of substantially quarter size relatively. That is, assuming that the said member was originally of disk shape and then quartered, the respective wings represent quarters that were retained, and the recesses between the same the spaces from which quarters were removed.

The overlapping and contact portions of members 4 and 5 are referred to herein as coming together and separating laterally, in contradistinction to the common way of separating by a relative sliding movement which changes the contact area. These contact members have no sliding movement but are stationary, and are pressed together by ratchet 6 and separate by their own spring action, and particularly the lower member, which springs away from the upper member the instant they drop off the ratchet surface behind shoulder *a*.

As usual, shell *E* is designed to be a separate and removable part of the socket to facilitate making electrical connections. But difficulty would be experienced in removing the shell if chain 16 passed through an eyelet mounted upon the shell. I therefore provide a separate eyelet member 21 having top and bottom flanges 18 adapted to seat within grooves or recesses in the upper and lower insulating disks or parts *A* and *B*, respectively and whereby said eyelet is rigidly held between said parts when assembled and secured together. Shell *E* is notched inward from its upper edge at 19, Fig. 13, to permit sleeving of the parts one over the other and obviously without removing chain 16 from eyelet 21. Again, the pull upon the chain is distributed from the eyelet to the solid insulating body parts 130

A and B and not upon the light shell E, and if necessary, the plate from which eyelet 21 is struck up, may be otherwise formed to fasten by screws to either or both of the body parts A and B.

What I claim is:—

1. A socket for incandescent lamps comprising two oppositely disposed insulating disks each having a contact member permanently fixed thereto on their opposed faces at one end and overlapping in their contact portions, and means to press said members together laterally without changing their relative positions in the socket comprising a rotatable insulating member mounted facially upon one of said disks opposite said contact members.

2. A socket for incandescent lamps having opposed insulating disks and substantially flat sided contact members mounted thereon on their opposed faces, and a rotatable ratchet member rotatably mounted on the inside face of one disk to press said members together laterally and a ratchet device to operate said ratchet member.

3. An incandescent lamp socket comprising upper and lower insulating disks and terminal connections separating the same and two substantially flat sided spring contact members normally separated and separately supported on said respective disks, a rotatable ratchet of insulating material adapted to have facial contact with one of said members to close and separate said contact members alternately, a lever to rotate said ratchet and a spring arranged to throw said ratchet back to starting position.

4. The combination of opposed insulating disks having a contact member on each and separated laterally from each other, with a rotatable ratchet member facially mounted upon one disk, a central post on which said ratchet is rotatably mounted, an operating lever sleeved on said post and adapted to rest on said ratchet to rotate the same, and a spring on said post to restore the lever to starting position.

5. An insulating ratchet member for electric lamp sockets having a central hub with a bore and a pair of segmental opposite wings spaced apart from each other, said wings each having a square shoulder at one edge and a tooth like projection at its top at the other edge and a flat inclined top surface between.

6. An insulating ratchet member for electric lamp sockets comprising a central hub having opposite segmental wings separated by segmental spaces and provided each with

a projection at one edge and top adapted to be engaged by a pawl and shouldered at its other edge for like engagement by contact members.

7. A socket for incandescent lamps comprising separable disks of insulating material and a switch embodied therewith and provided with a flexible connection to operate said switch, an eyelet member rigidly secured to said disks between the same and with which said flexible connection is adapted to have running engagement, and an enclosing shell for said disks separable therefrom and from said eyelet member.

8. A socket for incandescent lamps comprising upper and lower insulating disks spaced apart from one another and a switch between said parts having a flexible connection to operate the same, an eye member rigidly secured to the insulating disks between said parts through which said flexible connection extends, and a slotted shell adapted to sleeve over the socket parts and through which said eye member is adapted to project.

9. A socket for incandescent lamps comprising an insulating disk having a central boss and screw opening therethrough, a post and a screw to secure the same on said boss, a second insulating disk having a central opening, and terminal connections supporting said disks in spaced relation opposite each other, in combination with a spring contact member mounted upon each disk, and rotatable ratchet means mounted upon said post and adapted to press said contact members together.

10. A socket for lamps comprising upper and lower disks and terminal connections therefor adapted to support them in spaced relation, a contact spring mounted upon the opposed face of each disk and oppositely disposed and out of contact with each other, an insulating ratchet member having inclined faces to bring said springs into contact, a flanged post on the lower disk to rotatably support said member, notches in the flange of said post, a ratchet pawl sleeved about said post, a coiled spring adjustably engaged with said notched flange and adapted to return said pawl and means to operate said pawl.

In testimony whereof I sign this specification in the presence of two witnesses.

WILLIAM C. TREGONING.
